BASEBALL GAME APPARATUS

Joseph W. Bailey, Louisville, Ky., assignor of one-fourth to Andrew E. Miller, Terre Haute, Ind., and one-half to John L. Milton, Jefferson County, Ky.

Application June 22, 1932, Serial No. 618,598

16 Claims. (Cl. 273—89)

This invention relates to an electro-mechanical manual-automatic baseball game apparatus. The main object of the invention is to provide suitable apparatus by which a baseball game can be simulated with electro-mechanical apparatus organized to be played on an inclined board representing a playing field, provided with holes, lanes, runways, sub-runways, and balls to be batted thereover by manually actuated mechanical means together with electro-mechanical equipment to assist in effecting movements of the balls, which after batting and rolling in response to gravity simulate relative plays, positions and progress of the players, which are representative of action observed in a regular ball game.

An object of this device is to provide the operator with apparatus, with which he can actually play a game of baseball in miniature which will develop interest and thrills comparable to a game 20 played by humans in which his personality, skill and being constitute a part thereof.

Another object is to provide a manual-electro mechanical baseball game of a simple structure that will be rugged and entirely free from attention of an attendant or requiring burdensome instruction for its operation. In other words, a baseball game apparatus that with casual inspection will be self-explanatory to anyone having a knowledge of the great national game.

To assist in disclosing this invention reference is had to the accompanying drawings which are incorporated into this specification.

Figure 1 is a plan view of the top surface of the baseball apparatus carried on a table showing the 35 "infield" and the "outfield" and a portion of the operating apparatus, part in full lines and part in dotted lines, to present a general understanding of the entire device.

Fig. 2 is a transverse cross-sectional view of the 40 top surface and a substantially parallel sub-surface which cooperates therewith together with part of the major pieces of apparatus. This is shown disposed on an incline with reference to a dot-dash horizontal line which is included to indicate an understanding of the degree of inclination.

Fig. 3 is a perspective view of the major mechanical apparatus employed for starting the 50 game and clearing the board at the conclusion of an inning. Enough of this apparatus is shown in full and in dotted lines in Fig. 1 to establish its relation to the entire device.

Fig. 4 is a perspective view of a separate unit 55 employed to elevate balls to the playing field. Its location on the complete device can be gathered from Figs. 1 and 2 in which some of the parts are shown.

Fig. 5 is an enlarged scale elevation of a sole- 60 noid and its mounting shown in cross-section to-

gether with its movable members shown in full lines and its relation to the playing surface by means of a fragmental section of one of the base to base runways located adjacent the "diamond".

Fig. 6 shows a switch mechanism on a large 5 scale and the medium for operating same.

Fig. 7 is a wiring diagram of the entire electrical system.

Fig. 8 is substantially a cross-sectional view of Fig. 1, along line 8—8.

Fig. 9 is a top view of a portion of Fig. 8 plus some associated parts, with the deck removed.

Fig. 10 is an end view of the slide shown in Fig. 9.

Figs. 8, 9 and 10 disclose a part of the apparatus 15 employed to stop the game when the third "out" is made.

Figs. 11 and 12 show apparatus employed to accomplish the same function performed by the parts shown in Figs. 8, 9 and 10. Fig. 11 is a plan 20 view and Fig. 12 is a cross-section of Fig. 11, along line 12—12.

Fig. 13 is a modification of Fig. 5, while Fig. 14 is a top view of same.

Fig. 15 is a schematic drawing of a cam operated switch which is employed when the device shown in Figs. 13, 14 is employed.

The top of the table organized for this baseball game is indicated by numeral 10, referred to herein as the top deck, which is disposed at an angle 30 with reference to the horizon and is divided into two principal areas. 11 indicates the "outfield" and 12 indicates the "infield" mounted on deck 10 in dais formation, i. e. the infield, including the diamond and base to base runways, is actu- 35 ally elevated. The degree of elevation has been selected to prevent played balls from entering the runways except as planned for the normal operation.

This elevation also acts as a barrier to "lagging" balls into the base to base runways, 40 which in the earlier development models had been used to cheat or take advantage of the competitor or proprietor. At substantially the center of the infield, 13 indicates the pitcher's stand and is an opening in which is disposed tube 14, 45 slidably mounted in which is a plunger 15, fashioned with a rack that meshes with a segmental gear 16, which in turn is carried on a shaft 17 the fore end of which is journaled in bearing 18 mounted on the front of the table and the rear end carried in a journal formed in bracket 19, which is attached to the sub-top or deck 10a. Opening 16a in tube 14 is so disposed that balls 50 which are to be projected over the playing surface will gravitate toward the operator's end and finally reach said opening, likewise a ball delivered at 13 on the infield will gravitate toward the bat 20 which is pivoted at 21 in order that the operator may pull knob 22 in direction of the ar- 55

60

row and thereby strain spring 23 which upon release will bat or deliver the ball out over the playing surface. The ball may come to rest against the bat or the bat may be released as the ball approaches same. It will be perceived that different points of contact of the bat with the ball will result in variation in the travel of the batted ball according to the execution of the operator, which will be based on knowledge and acquired skill. Numeral 10b is an arched vertical wall, at the rear of top deck, against which a batted ball can strike and rebound.

Leading from the playing field to the infield are lanes A, B and C, the first one terminates at one corner of diamond 12 and is designated as first base A1. B communicates with the second corner and is designated by B1 as second base. C leads to third base and likewise is designated by C1 as third base. At each of these bases means are provided for arresting the played ball. Not only the playing field is inclined to cause the ball to roll forward, but each of the lanes is likewise disposed, and likewise the runways D, E and F flanking the diamond are inclined so that a ball coming through any one of the lanes and passing over any or all of the runways D, E and F, will pass into channel 30 where the ball will be arrested where its presence will indicate a run having been made.

31, 32, 33 and 34 are depressed local areas or sumps so disposed that a ball rolling into any one of them will fall through the apertures indicated by circles therein. Any ball passing through these apertures will pass on to the lower deck in which grooves are formed and indicated by the dotted lines leading therefrom and connecting with channel 35, the presence of a ball in same indicating an "out".

A ball passing through aperture 36 will find its way into groove or runway 37 formed in the lower deck 10a which follows the dotted lines into channel 30. It will be observed that a ball passes from the top deck into said runway and travels directly into channel 30 without having to stop or pass any of the bases. This corresponds to a "home run".

Entrance to lanes A, B and C and the home run aperture is gained only by passing groupings of staggered pins P, which are so organized as to retard the progress of a played ball to permit a formerly played ball to advance from base to base in response to the releasing treadle 41 and also to make the game difficult and to call for skill to place a ball at these entrances.

As a played ball passes through any of these lanes or through runway 37, it passes over one or more of the treadles 41 which are located in the decks by pin 42, Fig. 6, which carries another locating pin 43, this treadle is constructed so that it will be responsive to the weight of the ball and effects a contact between flexible strips 44, 45, which serve as springs to restore the treadle after the ball has passed and thereby energizes a portion of the electric circuit shown in Fig. 7, each of these switches being indicated in the figures by the numeral 6, except one of these switches which is indicated by 6a, this one being provided with an extra leaf and contact 6b to operate an electric bell. One switch is found in lane A, two in lane B, three in lane C, and three in runway 37. Current is supplied to the circuit through connector 46 and wires CX, DX. As any one of the contacts 6, 6a is closed an impulse of current is sent to all of the solenoids

indicated by the numeral 5, one being located at each base.

With reference to Fig. 5, it will be observed that the plunger 47 will be pulled down at each excitation of solenoid 481 against spring 48. Connected to this plunger is a pin 49 which extends through both decks. A plunger is found in Fig. 1 at each one of the bases A1, B1 and C1. The presence of this pin above the surface is so located in the groove of the runway that a ball will be lodged at and by same, however with its removal, which takes place with excitation of the solenoid, the lodged ball is freed thereby permitted to roll down the associated incline runway and will be lodged at the next base as pins 49 have been restored by springs 48. It is to be understood that all of these pins 49 are simultaneously actuated and each is organized to stop balls and permit them to pass in accordance with the operations of switches 6. A ball passing through lane A effects one movement of pins 49, through lane B two movements, through lane C and runway 37, three movements.

Balls failing to enter the lanes or the apertures, referred to heretofore, will gravitate over the surface of the outfield in areas adjacent apertures 59, 51, which are closed by slides 52, 53 disposed between the decks and are operable by cranks 54, 55 fixed on to shaft 56, (Fig. 3) which is rotatively mounted in bearings of brackets 57, 58 attached to the lower deck. Similarly actuated by 56 is slide 59, which is connected therewith by bar 91, shown in dotted lines on Fig. 1. This slide closes aperture 60 and prevents the balls indicating runs from passing off the deck 10a. Arm 61 also fixed to shaft 56 is connected by link 62 to arm 63 which is rotated about pivot 64, when actuated slide 65 engages the end of arm 63. Extension 66 of slide 65 has linked to it a lever for operating a switch 67 which functions as a master to energize the solenoids 481 and thereby free balls from the bases when starting a game. The actuation of the switch is simultaneous upon depositing a coin in hole 65a. The switch shown is connected into the electric circuit as shown in Fig. 7.

Also pivotally connected to 66 is rack 67a, the teeth of which are in register with teeth of pinion 68, connected on shaft 69 in such a manner that when the slide 65 travels in the direction of the arrow, it will slip over them, but will engage and be in mesh with said teeth on return stroke, the return stroke is effected by spring 70. On shaft 69 is fixed gear 71 which meshes with pinion 72 fixed to companion escapement gear 73, which actuates verge 74 to effect a time element for the purpose of holding switch 67 in engagement, which in turn holds all of the pins 19 down for a sufficient period of time to permit the balls to roll to a storage runway 80, simultaneously slides 52, 53 and 59 open their associated apertures and the balls from these areas are likewise led to runway 80.

Fixed to shaft 56 is arm 90, to which is articulated rod 91, the other end of which is articulated to slide 92, 92a, built in two sections and connected by spring controlled hinge 93. Both members of this slide are normally disposed in the same plane and the 92a section located so as to close orifice 35, Fig. 1, for the purpose of retaining played balls falling into the "out" classification on deck 10a until three balls are assembled. The third one of these being employed to actuate means resulting in operating means to block or stop the apparatus from being played

until slide 65 and its associated parts are again operated. Should there be only one or two balls in orifice 35 at the conclusion of an inning, determined by all allotted balls having been played, when slide 92, 92a is operated in unison with the parts affected by slide 65 for starting the game, they will drop into sub-runway 95 for recirculation. Fixed on shaft 17, cam 17b is disposed to swing lever 17c pivoted at 17d, the free end 10 of which engages and oscillates slide 96 mounted in sub-deck 10a and is positioned by compression spring 97 as indicated. This slide is equipped with a dog or detent 98, adjusted so as to clear lug 99 attached to 92a as it is moved forward 15 by 17c, as indicated by the arrow, provided there is only one or two balls, 99a, 99b present in orifice 35, however when the third ball 99c is present, detent 98 engages the spherical contour below the equator and is directed or carried down- 20 wardly, and the point engages lug 99 and rotates it on pivot 98a, and with further movement causes 92a to swing downwardly on hinge 93, thereby permitting all of the balls to discharge into sub-runway 95. Ball 99c following the sys- 25 tem of runways is caused to drop in trough 100 pivoted at 101, said trough having been balanced by counterweight 102 and located by stop 103 so that the weight of one ball will cause trough 100 to rock to the position shown in Fig. 2 and 30 thereby stop the other balls from entering opening 14a of ball feeding device shown in Fig. 4. Balls 99b and 99a follow 99c. Counterweight arm 93a is so related to the trough that upon operation of shaft 56 by slide 65, that it will inversely 35 swing it on pivot 101 and discharge the out balls into runway 86, thereby permitting the trough to respond to its counterweight and seek its normal rest position against stop 103. This position is up so that balls can enter tube 14 via opening 14a. 40 In the alternative method of stopping the game by the third out, ball as shown in Figs. 11 and 12, 105 indicates a runway 105 with bifurcated termini 106, 107, each having an aperture. 106 is closed by slide 92a while 107 leads directly 45 to sub-runway 95. The contour of runway 105 is such that the first two balls will lodge in 106 while the third one will contact the second one and be diverted into 107 from which it will pass on to trough 100 and stop the game as explained 50 supra.

The modification showing Figs. 13 and 14, the plunger 47 of Fig. 5 is located at the bottom of the windings indicated by the dotted lines in order that pin 49 will be forced up instead of pulled down when the winding is energized. Attached to 49 is a section of the cylinder 49a diagonally truncated to conform to the contour of the associated runway, and loosely registers with hole 49b and forms a part of a runway as indicated. 55 Stops 49c are provided to arrest the ball until the winding is excited, when the ball will be elevated or forced over said stops and allowed to proceed along the incline. In clearing the runways of balls lodged at the bases it is necessary to repeatedly operate plungers 49, consequently a cam 109, Fig. 15, fixed on shaft 69 (not shown in Fig. 3) will repeatedly close and open contacts carried in leaf springs 110 and 111 which in turn will energize the solenoids. Other methods can be employed to automatically cause the necessary electrical impulses to be transmitted to the solenoids. 65

Many modifications, alterations and combinations can be indulged without departing from the 70

spirit of my invention, therefore I wish to be limited only by the appended claims.

I claim:

1. A baseball game apparatus including balls and means for batting same and an inclined playing field consisting of an outfield and an infield elevated above the outfield, said infield including a pitcher's box and bases in diamond formation said bases being serially connected by runways. 5

2. A baseball game apparatus including balls and means for batting same and an inclined playing field consisting of an outfield and an infield elevated above the outfield, said infield including a pitcher's box and bases in diamond 15 formation said bases being serially connected by runways, means for introducing balls at said pitcher's box, inclined means to advance said ball toward said batting means. 10

3. A baseball game apparatus including balls 20 and means for batting same and an inclined playing field consisting of an outfield and an infield elevated above the outfield, said infield including a pitcher's box and bases in diamond 25 formation said bases being serially connected by runways, means for introducing balls at said pitcher's box, inclined means to advance said ball toward said batting means, in combination with three lanes extending from said outfield to the infield. 30

4. A baseball game apparatus including balls and means for batting same and an inclined playing field consisting of an outfield and an infield elevated above the outfield, said infield including a pitcher's box and bases in diamond 35 formation said bases being serially connected by runways, means for introducing balls at said pitcher's box, inclined means to advance said ball toward said batting means, means associated with the 1st, 2nd and 3rd bases for arresting a ball, in combination with three tortuous lanes extending from said outfield to the infield said lanes being equipped with means to retard the normal movement of a played ball in order that the ball lodged at one of the bases can be 40 released and advanced without interference from said played ball. 45

5. A baseball game apparatus including balls and means for batting same and an inclined playing field consisting of an outfield and an 50 infield elevated above the outfield, said infield including a pitcher's box and bases in diamond formation said bases being serially connected by runways, means for introducing balls at said pitcher's box, inclined means to advance said ball 55 toward said batting means, in combination with three lanes extending from said outfield to the infield, each leading to one of the bases to lead played balls to said bases.

6. A baseball game apparatus including balls 60 and means for batting same and an inclined playing field consisting of an outfield and a dais fashioned with a pitcher's box and bases in diamond formation which establishes an infield, means for introducing balls at said pitcher's box, 65 inclined means to advance said ball toward said batting means and means to lodge played balls at each of the bases, in combination with three lanes extending from said outfield to the infield, each leading to one of the bases to lead played 70 balls to said bases, means disposed in each of said lanes responsive to a played ball to actuate other means to advance lodged balls.

7. A baseball game apparatus including balls and means for batting same and an inclined play- 75

ing field consisting of an outfield and a dais fashioned with a pitcher's box and bases in diamond formation which establishes an infield, means for introducing balls at said pitcher's box, 5 inclined means to advance said ball toward said batting means and means to lodge played balls at each of the bases, in combination with three lanes extending from said outfield to the infield, each leading to one of the bases to lead played 10 balls to said bases, a plurality of means disposed adjacent each of said lanes to retard the otherwise normal movement of a ball passing therethrough, other means disposed in said lanes responsive to said ball to actuate other means to 15 advance lodged balls.

8. A baseball game apparatus including balls and means for batting same and an inclined playing field consisting of an outfield and infield having a base at each corner thereof, with inclined runways connecting said bases which are organized to stop played balls arriving thereat through lanes disposed in said outfield and leading to said bases, played balls receiving orifices in said outfield, sub-runways in communication 25 with all of said orifices, means disposed in said lanes and in one of said sub-runways operable by a played ball gravitating thereon in combination with other means to force any ball lodged at any base to advance towards the base next in 30 order to be occupied.

9. In a baseball game apparatus including balls and means for batting same and a pair of substantially parallel surfaces, the top one being an inclined playing field consisting of an outfield and 35 an infield having bases thereon equipped with means to stop played balls at said bases, lanes extending through said outfield and communicating with each base and ball receiving orifices in said outfield, runways in the lower surface and disposed in communication with all of said orifices, means disposed in said lanes operable by a 40 played ball gravitating thereon to actuate other means to advance any ball lodged at any base towards the base next in order to be occupied.

45 10. A baseball game apparatus including balls and means for batting same and a pair of substantially parallel surfaces, one of same being an inclined playing field consisting of an outfield and an infield having bases thereon equipped 50 with means to stop played balls at said bases, lanes extending through said outfield and each communicating with a base, ball receiving orifices in said outfield, runways in the other surface and disposed in communication with all of said orifices, means disposed in said lanes and one of 55 said runways operable by a played ball gravitating thereon in combination with other means to force any previously played ball lodged at any base away from same.

60 11. In a baseball game apparatus including balls and means for batting same, and a pair of substantially parallel surfaces, the top one being an inclined playing field consisting of an outfield and an infield having bases thereon, the latter being equipped with means to stop played balls thereat, runways extending through said outfield and communicating with each base and ball receiving orifices in said outfield, runways in the 65 lower surface in communication with all of said orifices, means disposed in the runways of the top surface operable by a played ball gravitating thereon to force any ball lodged at any base to

advance towards the base next in order to be occupied.

12. A baseball game apparatus including balls and means for batting same and an inclined playing field consisting of an outfield and an infield 5 in diamond formation having bases at each corner and inclined runways connecting said bases and lanes leading from the outfield to said bases, each of said bases being equipped with immovable means for detaining a played ball and movable 10 means for forcing said played balls past each of said immovable means, the incline of said inclined runways being a continuation of said inclined field and said lanes.

13. A baseball game apparatus including balls 15 and means for batting same and an inclined playing field consisting of an outfield and an infield in diamond formation having bases at each corner and inclined runways connecting said bases and tortuous lanes leading from the outfield to said bases, each of said bases being equipped with immovable means for detaining a played ball and movable means for forcing said played ball past each of said immovable means, 20 said lanes being equipped with means responsive to a played ball to actuate other means to actuate said movable means, the incline of said inclined runways being a continuation of said inclined field and said lanes.

14. A baseball game apparatus including balls 30 and means for batting same and an inclined playing field consisting of an outfield and an infield in diamond formation having bases at each corner and inclined runways connecting said bases and tortuous lanes leading from the outfield to said 35 bases, each of said bases being equipped with immovable means for detaining a played ball and movable means for forcing said played ball past each of said immovable means, said lanes being equipped with means responsive to a played ball 40 to actuate other means to actuate said movable means, said inclined runways being a continuation of said inclined field; ball receiving orifices in said outfield, sub-runways in communication with all of said orifices, a plurality of means disposed in one of said runways operable by a played ball 45 gravitating thereon to actuate said movable means.

15. A baseball game apparatus including balls a playing field and means for batting said balls 50 onto said playing field which is provided with bases and runways and means for putting said balls into play, means for arresting at the bases and means for advancing said played balls on said playing field, to simulate players of a baseball 55 game in which humans function, including a compartment in which "out" indicating balls are lodged, means operable by the third ball of a series of three balls diverted into said compartment, to prevent operation of said baseball game. 60

16. In a game apparatus, the combination of: an inclined playing board having a ball exit opening formed therein in the upper portion thereof; said playing board having a ball seat or pocket between said exit opening and the lower end 65 thereof; means for propelling balls one at a time onto the upper portion of said playing board so that they may gravitate thereover into said ball exit opening or into said ball seat; and means including an electromagnetic device actuated by a 70 ball passing through said exit opening to dislodge a ball from said ball seat.

JOSEPH W. BAILEY.
